DIRECT-CURRENT AMPLIFIER

Robert Terrance Cavanagh, Toronto, Ontario, Canada, assignor to Allen B. Du Mont Laboratories, Inc., Passaic, N. J., a corporation of Delaware

Application May 8, 1947, Serial No. 746,750

12 Claims. (Cl. 179—171.5)

1

This invention relates to an amplifier that is capable of providing voltage gains up to about 10^6 with very little if any distortion in a range of frequencies from direct current to about 50 kc. It is particularly suitable for amplifying signals of amplitudes less than 1000 microvolts.

With this invention a high frequency carrier is modulated to a high degree by a low level signal of frequencies from 0 to 50 kc. or above. Provision is made for tuning the circuits in accordance with the frequencies that are to be used. The percentage of modulation of the carrier can be controlled, and a low level carrier output voltage is made available so that high gain intermediate frequency amplification of the modulation envelope and carrier can be obtained without overloading and consequent distortion.

The invention may be understood from the description in connection with the accompanying drawing, in which

Fig. 1 is a block diagram of connections for the invention, and

Fig. 2 is a circuit diagram showing details of the invention.

Fig. 3 is a circuit diagram of another embodiment of the invention.

In the drawing, Fig. 2, reference characters 1 and 2 indicate pentodes having their cathodes and suppressor grids grounded. Biasing battery 3 is provided to bias the control grids of the tubes 1 and 2 negatively. A battery 4 is provided to supply current to the plates of the tubes 1 and 2 through resistances 5, 5', and variable inductances 6, 6' of the same sizes are in series with said resistances. A resistance 7 is provided between the screen grids of the tubes 1 and 2 with a sliding contact 8 thereon that is connected to an intermediate point on the battery 4.

Triodes 9 and 10 have their plates connected to a source of positive potential such as the battery 11 through lead 12. The control grids 13 and 14 of the tubes 9 and 10 are connected through resistances 15 and 16 respectively to the plates of the tubes 1 and 2.

Pentodes 17 and 18 have their screen grids connected respectively to the cathodes of the tubes 9 and 10. The cathodes and suppressor grids of the tubes 17 and 18 are grounded. The control grids of tubes 17 and 18 are connected to one end of the secondary 20 of a transformer T, to the primary 21 of which a carrier current e_2 is applied. The plates of tubes 17 and 18 are connected to opposite ends of the primary 22 of a transformer T' that has a source 23 of positive potential connected to a point half way between

2

the ends of this primary. A tuning condenser 24 is also connected between the ends of the primary 22. Either condenser 24 or the inductance of primary 22 may be varied to achieve resonance with the carrier frequency e_2 . The ends of this primary are connected to the plates 32 and 37 of tubes 17 and 18, respectively.

The secondary 25 of this transformer T' has a tuning condenser 26 connected across it and leads are provided at the ends of this secondary 25 for the output e_4 . Either condenser 26 or the inductance of secondary 25 may be varied to achieve resonance with the carrier e_2 .

Condenser 24 and inductance 22 and condenser 26 and inductance 25 are tuned so that the transformer T' has a band pass characteristic such that a flat response is obtained for 100 kc. on each side of the carrier frequency e_2 for a specified unbalance voltage on the screens of tubes 1 and 2.

20 The operation is as follows:

A direct or alternating current signal e_1 of small amplitude, which is to be amplified and used to modulate a high frequency carrier, is applied to the control grids of the push-pull amplifier 1,

25 2. If the contact 8 that is connected to battery 4 is not at the center of the resistance 7 that is connected between the screen grids of tubes 1 and 2, the circuit is unbalanced so that the outputs from the plates of tubes 1 and 2 differ thus causing a difference voltage, which may be designated e_3 to be developed between grid 13 of tube 9 and grid 14 of tube 10. The magnitude of this voltage depends upon the amount of unbalance of resistance 7 and/or the magnitude of the input voltage e_1 .

30 The voltage e_3 , which is that of the carrier frequency, is at the same time applied to the primary 21 of transformer T thus varying the plate currents of tubes 17 and 18 in parallel class B operation, the grid bias for this class of operation being supplied by battery 27.

35 Since the outputs of the tubes 1 and 2 are applied to the grids of tubes 9 and 10 and the outputs from the cathodes of these tubes 9 and 10 are applied to the screen grids 30 and 35 of tubes 17 and 18, the transconductances of tubes 17 and 18 are varied 180° out of phase in accordance with the input signal e_1 . The secondary 20 applies the carrier frequency e_2 to the control grids 29 and 34 of tubes 17 and 18 at the same time. By virtue of the fact that the cathode of tube 9 is connected to the screen grid 30 of tube 17, and the cathode of tube 10 is connected to the screen grid 35 of tube 18, the voltage between the screen grid 30

of tube 17 and the screen grid 35 of tube 18 varies in accordance with the input voltage e_1 .

A brief analysis of the operation is as follows:

Let the voltage from grid 29 to cathode 28 of tube 17 be e_{g1} , the voltage from grid 34 to cathode 33 of tube 18 be e_{g2} , the voltage from screen grid 30 of tube 17 to screen grid 35 of tube 18 be e_4 , the voltage from screen grid 30 to cathode 28 be e_5 , and the voltage from screen grid 35 to cathode 33 be e_6 .

$$\text{Then } e_4 = e_5 + e_6$$

Let the carrier voltage appearing in the grid circuit be e_7 , and the battery 27 voltage be E .

$e_7 = C \cos w_7 t$ where C is a constant, $w_7 = w_2$, where w_2 is the angular frequency of the carrier voltage e_2 .

$$\begin{aligned} e_{g1} &= E + e_7 & e_{g2} &= E + e_7 \\ i_{p1} &= g_{m1} e_{g1} & i_{p2} &= g_{m2} e_{g2} \\ i_{p1} &= g_{m1}(E + e_7) & i_{p2} &= g_{m2}(E + e_7) \end{aligned}$$

but g_{m1} is a function of e_7 and e_{g1} , or $g_{m1} = f(e_{g1}, e_7) = a_1 + b_1 e_8 + c_1 e_8^2 + d_1 e_8^3 + \dots$ where

$$e_8 = A_5(1 + \cos W_5 t) + B_1(E + \cos w_7 t)$$

The frequency of the input voltage e_1 is

$$f_5 = \frac{w_5}{2\pi} = \frac{w_1}{2\pi}$$

where w_1 = the angular frequency of input voltage e_1 .

A_5 is a constant depending on the voltage from screen grid 30 to cathode 28 of tube 17, and the relative effect of this screen voltage on the transconductance g_{m1} . B_1 is a constant depending on the relative effect of grid voltage e_{g1} on the transconductance g_{m1} .

$$g_{m2} = a_2 + b_2 e_9 + c_2 e_9^2 + d_2 e_9^3 + \dots \text{ where}$$

$$e_9 = A_6(1 + \cos w_6 t) + B_2(E + \cos w_7 t).$$

A_6 and B_2 are the same to g_{m2} as A_5 and B_1 to g_{m1} above and

$$f_6 = \frac{w_6}{2\pi} = \frac{w_1}{2\pi}$$

where w_1 is as specified above.

If the g_m series are assumed to converge, a finite value of plate current is obtained for each tube. This plate current contains all the usual modulation components, those of importance being of frequencies w_2 , $(w_2 - w_1)$ and $(w_2 + w_1)$.

The output voltage e_0 depends on the difference plate current components $i_{p1} - i_{p2}$. Thus with slight static off-balance of the input voltage e_4 to the modulator by means of tap 8 on resistor 1, the output voltage e_0 contains components of frequencies w_2 , $(w_2 - w_1)$, $(w_2 + w_1)$.

The transformer T' is tuned for a band pass characteristic of 200 kc. so that only the carrier frequency and usual sideband frequencies appear as components of the output voltage e_0 from T'. The output voltage e_0 is a conventional amplitude modulated wave of carrier frequency e_2 , which may for example be 4.0 mc., the modulation envelope being determined by the amplitude and frequency of e_1 .

The output from the secondary 25 is fed to the first intermediate frequency amplifier indicated in Fig. 1. The remaining portion of Fig. 1 indicates the conventional D. C. means for detecting and observing a signal that has been transmitted by a carrier.

In Fig. 2, batteries are shown as supplying the potentials necessary for operation. The same results may be achieved by using conventional power supplies and self biasing arrangements

employing cathode resistors in the well-known manner.

Fig. 3 is a diagram showing another embodiment of the invention. In this embodiment the screen currents of tubes 17' and 18' are supplied through the plate loads 38, 39 and 40, 41 of tubes 1' and 2', respectively. This eliminates the cathode follower tubes 9 and 10 of Fig. 2. The operation is similar to that of Fig. 2.

10 What is claimed is:

1. An amplifier for low amplitude signals which comprises push-pull pentodes, one of which has its screen grid biased to a higher potential than the other, cathode follower tubes to which the outputs of said pentodes are respectively coupled, a modulator to which the cathodes of said follower tubes are coupled and means to apply a carrier signal to said modulator.

2. The amplifier of claim 1 in which said cathode follower tubes are triodes having their grids coupled to a source of direct current.

3. The amplifier of claim 1 in which the cathodes of said follower tubes are connected to the screen grids of said modulator.

25 4. The amplifier of claim 1 in which said carrier signal is coupled to the control grids of said modulator.

5. The amplifier of claim 1 in which said push-pull pentodes are unbalanced.

30 6. The amplifier of claim 1 in which means are provided to apply an input signal to the control grids of said push-pull pentodes.

7. An amplifier for low amplitude signals by means of which a radio frequency carrier is modulated to a high degree, which comprises a pair of pentode vacuum tubes connected in push-pull with a frequency response between 0 and about 50 kilocycles per second, said amplifier being unbalanced by means of controlled transconductances of said tubes, separate cathode follower stages driven by said amplifiers, two additional pentode vacuum tubes having their screen grids connected to the outputs of said cathode follower stages, said last mentioned tubes having impressed upon their control grids a voltage of carrier frequency, a tuned transformer being provided as the push-pull plate load of said last mentioned pentodes, whereby an output voltage is produced comprising said carrier frequency voltage and side-band frequency voltage components thereof.

50 8. The amplifier of claim 7 in which said cathode follower stages are triodes.

9. An amplifier for low level signals by means 55 of which a radio frequency carrier is modulated to a high degree which comprises a pair of pentode vacuum tubes connected in push-pull with a frequency response between 0 and about 50 kilocycles per second, said amplifier being unbalanced by means of controlled transconductances of said tubes, two additional pentode vacuum tubes having their screen grids connected respectively to the plates of said last mentioned tubes, the control grids of said last mentioned tubes 60 being connected in parallel and having impressed thereon a voltage of carrier frequency, a tuned transformer being provided as the push-pull plate load of said last mentioned pentodes, whereby an output voltage is produced comprising said carrier frequency voltage and side-band frequency voltage components thereof.

10. A device for amplitude modulating a high frequency carrier wave which comprises push-pull pentodes having their control grids connected to a source of carrier voltage and their

screen grids having unbalanced symmetrical input signals connected thereto, and a resonant circuit tuned to said carrier frequency connecting the plates of said pentodes.

11. A device for amplitude modulating a high frequency carrier wave which comprises push-pull pentodes having their control grids connected to a source of carrier voltage and their screen grids having unbalanced symmetrical input signals connected thereto from a push-pull amplifier, and a resonant circuit tuned to said carrier frequency connecting the plates of said pentodes.

12. A device for amplitude modulating a high frequency carrier wave which comprises push-pull pentodes having their control grids connected to a source of carrier voltage and their

screen grids having unbalanced symmetrical input signals connected thereto from a push-pull amplifier in which the screen grids are unbalanced as to the potential at which they are maintained, and a resonant circuit tuned to said carrier frequency connecting the plates of said pentodes.
